UNITED STATES PATENT OFFICE

114,254

DESIGN FOR A COMBINED GLASS SCRAPER AND GUARD THEREFOR OR SIMILAR ARTICLE

Herman Siemund, Chicago, Ill., assignor to Greenview Manufacturing Company, Chicago,
Ill., a corporation of Illinois

Application July 19, 1938, Serial No. 78,574

Term of patent 14 years

To all whom it may concern:

Be it known that I, Herman Siemund, a citizen of the United States and resident of Chicago, Illinois, whose post-office address is No. 2557 Greenview Avenue, Chicago, Illinois, have invented a certain new, original, and ornamental Design for a Combined Glass Scraper and Guard Therefor or Similar Article, of which the following is a specification, reference being had to the accompanying drawing, forming a part thereof, wherein:

Fig. 1 is a front elevational view of a combined glass scraper and guard therefor or similar article, in closed position, embodying my new design, with an intermediate portion of the handle broken away for convenience of illustration;

Fig. 2 is an exploded front elevational view thereof with the guard in Fig. 1 removed;

Fig. 3 is an exploded side elevational view thereof with the guard in Fig. 1 removed;

Fig. 4 is an exploded rear elevational view thereof with the guard in Fig. 1 removed; and

Fig. 5 is a side elevational view of Fig. 1.

What I claim is:

The ornamental design for a combined glass scraper and guard therefor or similar article, substantially as shown and described.

HERMAN SIEMUND.
